UNITED STATES PATENT OFFICE.

CHRISTOPHER M. KEENAN, OF DETROIT, MICHIGAN.

TRAFFIC-SIGNAL FOR AUTOMOBILES.

1,151,953.

Specification of Letters Patent. Patented Aug. 31, 1915.

Application filed May 14, 1913. Serial No. 767,553.

To all whom it may concern:

Be it known that I, CHRISTOPHER M. KEENAN, a citizen of the United States, residing at Detroit, county of Wayne, State of Michigan, have invented a certain new and useful Improvement in Traffic-Signals for Automobiles, and declare the following to be a full, clear, and exact description of the same, such as will enable others skilled in the art to which it pertains to make and use the same, reference being had to the accompanying drawings, which form a part of this specification.

This invention relates to traffic signals for automobiles and its object is a device by means of which the intended movement of the vehicle may be made known and is to be mounted upon the side thereof whereby it may be observed from either the front or the rear of the vehicle, the arrangement of the device being such that a similar signal or indication is simultaneously brought to view upon both the front and back of the device.

A further object is a simple and comparatively inexpensive device for the purpose which is reliable and efficient in use and is controlled manually by the operator of the vehicle.

With the above and other objects in view the invention consists in the novel features of construction and arrangement of parts hereinafter more fully described and claimed and shown in the accompanying drawings in which—

Figure 1 is a perspective view of a signal embodying my invention. Fig. 2 is a longitudinal section thereof. Fig. 3 is a cross section on line X—X of Fig. 2.

Similar characters refer to similar parts throughout the drawings and specification.

The device consists of a cylindrical casing 1 adapted to be mounted upon the side of the vehicle by means of a bracket 2 and is provided upon opposite sides thereof with similar slots 3 and 4. The casing 1 has a cover 5 and the cover 5 and the closed end of the casing 1 are adapted to rotatably support a shaft 7. Secured to the shaft 7 in such manner as to be rotatable therewith is an inner cylindrical casing 8 bearing a duplicate series of words such as "stop", "cross", "turn", "back" etc., and these words are so placed upon the inner cylinder that a similar word is simultaneously exposed to view in both

slots 3 and 4 in the casing 1, whereby those in the front and the rear of the vehicle may be apprised of its intended movement.

The inner cylinder 8 may either be formed of translucent or transparent material or that portion of the cylinder bearing the words may be so formed and the words may be either painted upon the transparent or translucent material or such material may be covered with an opaque paint or the like and the letters formed therein by a cutting away of such opaque material.

The inner casing 8 has an open end adjacent the cover 5 for the outer casing as is shown in Fig. 2 and mounted upon the cover 5 for the outer casing which is stationary and extending into the casing 8 is an electric light bulb which may be supplied with current in any well known manner and which is to be used at night in order that the various words may be properly displayed. The device should be of such size that the words may be made sufficiently large to be seen a considerable distance from the vehicle.

The shaft 7 upon which the inner cylinder is mounted extends outwardly from the device a sufficient distance to be within ready reach of the operator and is provided with a hand wheel 9 by means of which it may be manually operated.

Upon the shaft 7 and contiguous to the stationary cover 5 of the casing 1 is a ratchet wheel 10, the teeth of which are engaged by a spring pressed plunger 11 mounted upon the stationary cover 5, the teeth of the ratchet being so positioned that the plunger 11 when in engagement therewith holds the inner cylinder from accidental rotation but is yieldable whereby the cylinder may be readily rotated by the hand-wheel.

The device is preferably mounted upon the side of the vehicle near the seat so that the hand wheel 9 may be readily reached by the operator and the device is in such position that the displayed word or signal may be observed by the operator.

Therefore what I claim as new and desire to secure by Letters Patent of the United States is—

1. In a device of the character described, in combination, a casing provided with a display opening at the front and rear sides thereof, said casing having a closed and an open end, a detachable cover for said open end, a second casing rotatably mounted

within said first named casing having an open end adjacent the open end of the outer casing and also bearing a multiple series of words or signals adapted to indicate the intended movement of the vehicle, a like word or signal in each series being simultaneously displayed through each opening in the outer casing, said words or signals being placed or formed on transparent or translucent material, illuminating means supported upon the said cover for the outer casing and extending into the open end of the inner casing, and means for rotating said inner case.

2. In a device of the character described, in combination, a casing provided with a display opening upon the front and rear sides thereof, said casing having a closed and an open end, a shaft extending centrally therethrough and extending through an aperture provided in the closed end, a cover for the open end also provided with an aperture through which said shaft extends, a second casing within said first named casing having an open end adjacent the open end of the outer casing, said inner casing being fixed to the shaft and rotatable therewith, and also bearing a multiple series of words or signals adapted to indicate the intended movement of the vehicle, a like word or signal in each series being simultaneously displayed through each slot in the outer casing, said words or signals being placed or formed on translucent or transparent material, illuminating means supported upon the said cover for the outer casing and extending into the open end of the inner casing, and means for rotating said shaft.

3. In a device of the character described, in combination, a casing provided with a display opening at the front and rear sides thereof, said casing having a closed and an open end, a detachable cover for said open end, a second casing rotatably mounted within said first named casing having an open end adjacent the open end of the outer

casing and also bearing a multiple series of words or signals adapted to indicate the intended movement of the vehicle, a like word or signal in each series being simultaneously displayed through each display opening in the outer casing, said words or signals being placed or formed on transparent or translucent material, illuminating means supported upon the said cover for the outer casing and extending into the open end of the inner casing, means for rotating said inner casing, and a bracket secured to the outer casing by means of which the device may be supported upon a vehicle and whereby said outer casing is held from rotation.

4. In a device of the character described, in combination, a casing provided with display openings at the front and rear sides thereof respectively, said casing having a closed and an open end, a detachable cover for said open end, a shaft extending through said casing and cover, a second casing mounted within the said first named casing secured to said shaft and having an open end adjacent the open end of the outer casing, said inner casing also bearing a multiple series of words or signals adapted to indicate the intended movement of the vehicle, a like word or signal in each series being simultaneously displayed through each display opening in the outer casing, said words or signals being placed or formed on translucent or transparent material, an electric light supported upon the said cover for the outer casing and extending into the open end of the inner casing, means for rotating said shaft and means for yieldably holding the said shaft in position to display either of the words or signals.

In testimony whereof, I sign this specification in the presence of two witnesses.

CHRISTOPHER M. KEENAN.
